[57] CLAIM

We claim the ornamental design for a baby stroller, as shown and described.

DESCRIPTION

FIG. 1 is a perspective view of the baby stroller of the present invention.

FIG. 2 is a right side view of the baby stroller of FIG. 1, the left side view being a mirror image of that shown.

FIG. 3 is a front view thereof;

FIG. 4 is a rear view thereof;

FIG. 5 is a top view thereof; and,

FIG. 6 is a bottom view thereof.
